UNITED STATES PATENT OFFICE.

MARTIN HEMLEB, OF ELIZABETH, NEW JERSEY, ASSIGNOR TO THE SINGER MANUFACTURING COMPANY, A CORPORATION OF NEW JERSEY.

ROTARY-HOOK SEWING-MACHINE.

1,280,728.

Specification of Letters Patent.

Patented Oct. 8, 1918.

Application filed October 18, 1916. Serial No. 126,237.

To all whom it may concern:

Be it known that I, MARTIN HEMLEB, a citizen of the United States, residing at Elizabeth, in the county of Union and State 5 of New Jersey, have invented certain new and useful Improvements in Rotary-Hook Sewing-Machines, of which the following is a specification, reference being had therein to the accompanying drawings.

10 This invention relates to that type of rotary hook sewing machines in which the hook or loop-taker makes a plurality of rotations to one reciprocation of the needle and has for an object to provide effective 15 means for driving said loop-taker when secured upon a vertical shaft by a connection with the horizontal main or driving shaft. Heretofore such a connection between the main and loop-taker shafts has been effected 20 by employment of an intermediate or lower horizontal shaft, one end of which was connected to the loop-taker shaft through a pair of speed-multiplying bevel gears. The opposite end of the intermediate shaft was 25 driven through the usual pitmen connections with a pair of quartered cranks formed on the main-shaft. The use of bevel gears beneath the bed-plate is undesirable as they are more or less noisy in operation and re- 30 quire special housing to provide for proper lubrication and to prevent introduction of dirt and grit to impair their effectiveness and durability.

The present invention is designed to obviate the use of intermeshing gears beneath the bed-plate, to reduce vibration caused by reciprocating or unbalanced connections, and to provide a light weight machine better adapted for high speed and quiet operation 40 than those heretofore used.

According to the present improvement the main-shaft, journaled in the overhanging arm, is connected by speed-multiplying bevel gears to an upright shaft journaled with- 45 in the hollow bracket-arm standard and provided at its lower end with angularly disposed cranks connected by pitmen to similar cranks upon the vertical hook-shaft upon which the loop-seizing member is se- 50 cured for coöperation with the usual reciprocating needle.

In the drawings, Figure 1 is a side elevation of a sewing machine embodying the present improvement with the frame partly

in section, and Fig. 2 is a bottom plan view 55 of the same.

The frame of the machine comprises the usual bed-plate 1 from which rises the hollow bracket-arm standard 2 having the tubular lateral member 3 within which is 60 journaled the main or driving shaft 4 having the usual operative connection with the reciprocating needle-bar 5 carrying the needle 6.

Depending from the bed-plate 1 is the 65 bearing bracket 7 in which is journaled the vertical loop-taker shaft 8 having secured thereon by means of the set-screw 9 the hub 10 of the cup-shaped loop-seizing member 11 provided with the beak 12, in which is 70 journaled in a manner well-known the thread-case 13.

The lower end of the loop-taker shaft 8 has secured thereon by means of a suitable set-screw (not shown) the hub 14 of a crank 75 member provided with the crank-studs 15 and 16 disposed in offset relation relatively to the shaft 8, and a similar crank element 17 is fixed upon the lower end of the vertical intermediate shaft 18 which is journaled within the bearing bosses 19 and embraced by the standard 2. The crank-studs of the shafts 8 and 18 are connected by means of the pitmen 20 to establish driving relation 80 between said shafts. The shaft 18 has fixed upon its upper end the bevel pinion 21 meshing with the bevel gear 22 of double its size 85 fixed upon the main-shaft 4 by which the intermediate shaft is driven at twice the speed of the main-shaft, its movements being imparted to the loop-taker shaft through the described crank-and-pitmen connection. 90

By the means thus described, the speed-accelerating gears 21 and 22 are housed 95 within the bracket-arm where they are protected from foreign matter which would impair their effectiveness, and the connections with the loop-taker shaft beneath the bed-plate are of a pivotal character so as to exclude lint and grit thrown off in the stitching operation while insuring noiselessness and durability in operation. 100

It will be noted that the main-shaft is not unbalanced by the presence of quartered cranks which in prior constructions tend to cause excessive vibration of the tubular arm toward and from the operator if high speed operation is attempted. In the present con- 105

struction the quartered cranks act in horizontal planes beneath the bed-plate and since their only function is to drive the vertical loop-taker shaft directly they, together with the connecting pitmen, may be made very light in weight.

Having thus set forth the nature of the invention, what I claim herein is:—

In a sewing machine, a frame comprising 10 a bed-plate, hollow standard and bracket-arm, a reciprocating needle carried by the bracket-arm, a needle-driving shaft journaled in the bracket-arm, a loop-taker, a loop-taker shaft journaled beneath the bed- 15 plate in parallelism with the needle-path, a pair of angularly related cranks carried by

the loop-taker shaft and disposed below the bed-plate, and means for driving said loop-taker shaft at a uniform angular velocity, said means including a vertical shaft journaled in said standard and provided beneath the bed-plate with angularly related cranks, a driving connection including speed multiplying gearing between the needle-driving and vertical shafts, and parallel pitmen disposed horizontally beneath the bed-plate and connecting the cranks of said vertical and loop-taker shafts.

In testimony whereof, I have signed my name to this specification.

MARTIN HEMLEB.
